(57) **CLAIM**

The ornamental design for an omnidirectional wireless microphone for use with a multi-user audio system, as shown and described.

DESCRIPTION

FIG. 1 is a front perspective view of an omnidirectional wireless microphone for use with a multi-user audio system; FIG. 2 is a back perspective view of an omnidirectional wireless microphone for use with a multi-user audio system; FIG. 3 is a front view of an omnidirectional wireless microphone for use with a multi-user audio system; FIG. 4 is a side view of an omnidirectional wireless microphone for use with a multi-user audio system; FIG. 5 is a back view of an omnidirectional wireless microphone for use with a multi-user audio system; FIG. 6 is a side view of an omnidirectional wireless microphone for use with a multi-user audio system; FIG. 7 is a bottom view of an omnidirectional wireless microphone for use with a multi-user audio system; and, FIG. 8 is a top view of an omnidirectional wireless microphone for use with a multi-user audio system.

The broken lines form no part of the claimed design.
